RADIO TUBE SOCKET

Albert W. Franklin, New York, N. Y.

Application April 10, 1943, Serial No. 482,565

2 Claims. (Cl. 173—328)

This invention involves improvements in radio tube sockets for special use with the ultra high frequency type of tube known in the art as the "acorn" tube.

The main object of this invention is to provide an ultra high frequency radio tube socket which is extremely simple in construction and particularly characterized by the features of construction of the pin receiving contacts forming a part thereof.

A particular object of the invention is to provide a contact for sockets of this type which insures good electrical engagement with the tube pins and which maintains this contact under the normal intensities of vibration to which such devices are subjected.

A further object of the invention is to provide contact clips for this purpose which require a minimum of effort to insert and remove the pins while maintaining good contact with the pins under the severest vibration conditions normally to be encountered.

A more detailed object of this invention is to provide a terminal pin clip so constructed as to normally act to maintain firm mechanical and electrical engagement with the tube pins.

These and other detailed objects successfully secured by the structure herein disclosed will be fully described in the following specification when taken in connection with the attached drawing.

This invention resides substantially in the combination, construction, arrangement and relative location of parts as will be described in detail below.

In the accompanying drawing:

Figure 1 is a top plan view of a radio tube socket with terminal clips constructed in accordance with this invention;

Figure 2 is a cross-sectional view taken on the line 2—2 of Figure 1; and

Figure 3 is a front elevational view, somewhat enlarged, of one of the contact clips.

The socket of this invention includes a base or support 10 of any suitable configuration as, for example the ring or washer-like formation illustrated. This support may be made of any proper insulating material available for efficient use especially at ultra high frequencies and, for example, may be a ceramic material. The base is provided with a pair of holes 11 by means of which it may be attached to a suitable support in the apparatus of which it is to form a part.

Mounted on the support and, as illustrated, extending radially with respect thereto are a plurality of terminal pin clips or contacts 12 secured to the support in any suitable manner as, for ex-

ample, by means of the riveted eyelets 13. Each clip 12 is formed from a single piece of suitable resilient metal such as, for example, phosphor bronze preferably heavily silver plated to provide low contact resistance with the tube pins.

Each clip includes what may be called a base plate 14 which terminates at one end in a downwardly extending integral tip 15 adapted to lie in an axial slot 16 on the inner face of the support 10 as is clear from Figures 1 and 2. The opposite end of the base plate is provided with an aperture 17 by means of which a circuit wire may be hooked thereto and soldered in place in accordance with the usual practice. Extending along the opposite sides of the base plate 14 and integral therewith are a pair of upstanding walls 18 which have a vertical relation with respect to the plane of the base plate 14. The inner ends of the side walls are cut free of the base plate, as is clear in Figures 2 and 3, and are bent so as to lie in converging planes towards the center of the support. The terminal ends 19 of the converging wall portions are bent towards each other so as to extend towards each other, as is clearly illustrated in the front end elevational view of Figure 3. The upper edges of the ends 19 are smoothly curved in a downward direction into a pair of straight edges which diverge downwardly into curved edges which terminate in overlapping tips 20.

As will be seen from the type of socket illustrated, the clips are adapted to receive the tube terminal pins by movement in an axial direction towards the support 10 as is true of the acorn type of tube whose terminal pins radiate from the base thereof. One terminal pin is shown in cross-section at P in Figure 3 in the position it will assume when the tube is in the socket. In order to reach this position the pin is applied to the top curved edges of the end walls 19 of the clip and is guided smoothly as it is forced downwardly to a position to cause the converging side walls to move apart to allow the entry of the pin P into the more or less similarly shaped seat defined at the lower diverging edges of the end walls. The downward movement of the pins is limited by the overlapping tips 20 and the adjacent edges of the end walls 19 being inclined, as shown, exert downward pressure on the pin P causing it to be firmly seated on the tips 20 and to be firmly engaged at opposite sides of the inclined edges. Thus each pin has at least three points of contact with each clip insuring good mechanical and electrical contact between the pins and the clips. The result is a firm engage-

ment of the clips with the pins to resist vibration while maintaining excellent electrical contact therebetween. By reason of the shape of the co-operating edges of the end walls 18 the pins may be relatively easily withdrawn forcing the flexible converging side walls apart as the pin is withdrawn. The upper curved edges aid in properly aligning the tube with the socket at the time pressure is applied to seat the pins.

From the above description those skilled in this art will readily appreciate the advantages and utility of the structure herein disclosed and will be aware of possible modifications thereof while employing the novel subject matter herein disclosed. I do not, therefore, desire to be strictly limited to the disclosure given herein in an illustrative sense but rather by the scope of the claims granted me.

What is claimed is:

1. An electrical contact terminal clip of metal comprising a bottom wall, a pair of parallel side walls attached to said bottom wall, and a pair of opposed ears at the corresponding ends of the side walls defining a constricted slot closed on one end and open at the other, said side walls being detached from the bottom wall at the edges adjacent said ears and said ears having overlapping extensions forming the closure for the closed end of the slot.

2. In the combination of claim 1, said slot being divergent from a point of constriction towards its closed end.

ALBERT W. FRANKLIN.
